(57) **CLAIM**

The ornamental design for a motorquick switch, as shown and described.

DESCRIPTION

FIG. 1 is a front elevational view of the motorquick switch in accordance with a first embodiment of the present invention;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front elevational view of the motorquick switch in accordance with a second embodiment of the present invention;

FIG. 8 is a rear elevational view thereof;

FIG. 9 is a left side elevational view thereof;

FIG. 10 is a right side elevational view thereof;

FIG. 11 is a top plan view thereof;

FIG. 12 is a bottom plan view thereof;

FIG. 13 is a front elevational view of the motorquick switch in accordance with a third embodiment of the present invention;

FIG. 14 is a rear elevational view thereof;

FIG. 15 is a left side elevational view thereof;

FIG. 16 is a right side elevational view thereof;

FIG. 17 is a top plan view thereof; and,

FIG. 18 is a bottom plan view thereof.

The broken line showing in the figure drawings is included for illustrative purposes only and forms no part of the claimed design.
